(57) **CLAIM**

We claim the ornamental design for a double-handle box, as shown and described.

DESCRIPTION

FIG. 1 is a perspective view of a double-handle box, showing my new design in a partially open position.

FIG. 2 is another perspective view thereof, showing a side flap bent fully outward.

FIG. 3 is a top plan view of the claimed design of FIG. 1.

FIG. 4 is a bottom plan view thereof.

FIG. 5 is a front elevation view thereof.

FIG. 6 is a rear elevation view thereof.

FIG. 7 is a first side or left side elevation view thereof.

FIG. 8 is a second side or right side elevation view thereof.

FIG. 9 is a top perspective view thereof.

FIG. 10 is a perspective view of the claimed design of FIG. 1 in a partially assembled flattened condition.

FIG. 11 is a top plan view thereof in a fully unfolded condition. A bottom plan view of the blank is a mirrored image of the top plan view.

FIG. 12 is a right top perspective view of the claimed design of FIG. 1 showing both side flaps thereof bent inward and a front flap thereof bent partially inward.

FIG. 13 is a perspective view thereof in a condition of use.

FIG. 14 is another perspective view thereof in a condition of use showing an alternate configuration; and,

FIG. 15 is an enlarged view thereof taken from detail 15 of FIG. 8.

Those features shown in broken lines in FIGS. 13 and 14 illustrating a user holding the double-handle box form no part of the claimed design. The short-short-long dash broken lines in FIGS. 8 and 15 designating the boundary of the enlarged view form no part of the claimed design.
